7 Claims. (Cl. 250—11)

This invention relates to radio direction finding systems and has for its object to provide an improved receiver arrangement wherein the direction of a radio beacon or other transmitting station is indicated by the clear reception of a television picture.

A further object of the invention is to provide an improved system wherein the level of the synchronized impulses provided at the receiver for synchronizing the receiving television scanning apparatus with the transmitting television scanning apparatus shall be received at a substantially constant level.

Arrangements wherein television transmission and reception are employed for direction finding purposes are described in the specifications accompanying co-pending application Serial No. 672,552, filed May 24, 1933.

It is very desirable for practical reasons that when a receiving station equipped with television apparatus and employed for bearing finding and directional purposes has its receiving aerial system correctly oriented to obtain a bearing on a particular beacon or transmitter, the received television picture obtained from that beacon or transmitter should appear clearly and the principal object of the present invention is to provide an improved receiver arrangement whereby this is achieved, the received picture being only received clearly when the aerial system is correctly oriented or approximately correctly oriented and the character of the said received picture clearly visibly different for other orientations of the receiving directional aerial system.

According to this invention a receiving television station for use for bearing finding and similar purposes comprises a frame or equivalent directional receiving system, an open aerial or equivalent substantially non-directional receiving system, a television scanning and picture synthesizing system, means for building up by means of said scanning and picture synthesizing system a picture derived from signals received upon the substantially non-directional aerial system, and means for superimposing upon said signals, signals of reverse phase derived from the directional aerial system.

The directional aerial system may take any convenient form: for example, it may be constituted by a rotatable frame aerial or by a Bellini-Tosi aerial system in co-operation with a radiogoniometer and similarly the substantially non-directional aerial system may take different forms, for example, it may be constituted simply by an open aerial or, where a Bellini-Tosi directional system

is employed, the vertical effect of said system may be utilized in manner known, per se, for non-directional reception.

The phase reversal of the signals from the directional system with respect to those from the non-directional system may be obtained in any convenient way, for example, a low frequency amplifier following the detector energized from the directional system may contain one more or one less stage of magnification than the corresponding low frequency amplifier following the detector energized from the non-directional aerial system or, again, the type of detection employed for the signals received from the directional system may be different from that employed for the signals from the non-directional system, leak grid detection being employed for one set of signals and anode bend detection for the other.

It will be seen that with arrangements in accordance with the present invention the signals received by the directional system will be substantially non-existent when that system is correctly oriented to the direction of the station being received, and in carrying out the present invention the arrangement is preferably made such that within a predetermined number of degrees of the correct bearing direction, e. g. within 10 degrees of that direction, the strength of signals received from the directional aerial system is approximately the same as that from the non-directional system. Thus, since the effect of the superimposition in the picture synthesizing apparatus of the signals received from the directional system upon those received from the non-directional system is to superimpose a picture which is, as it were, a negative of the picture from said non-directional system, it will be apparent that within the predetermined limit of 10 degrees or thereabouts there will be a sharp contrast in the total received picture as between the combined positive and negative pictures obtained when the signals from both aerial systems are about the same strength and the clear positive picture obtained at the correct bearing position when the signals from the directional system are substantially non-existent.

The invention is illustrated in the accompanying diagrammatic drawing which shows a receiving station in accordance therewith.

Referring to the drawing a tuned rotating frame aerial A tuned by a condenser as shown is employed as the directional system and the signals obtained therefrom are applied, after amplification at the carrier frequency by means of a valve V₁, between the grid and cathode of a

thermionic valve V_2 to which the requisite potentials are applied to cause said valve to operate as an anode bend detector. This detector valve is resistance capacity coupled to a triode V_3 in cascade therewith and acts as a common amplifier both for the directionally received signals and the non-directionally received signals. The non-directionally received signals are picked up upon a vertical aerial B which is tuned in the usual way by a condenser as shown, the signals from this aerial being applied, after amplification at the carrier frequency, if desired, between the grid and cathode of a triode V_4 in whose grid lead is inserted the usual grid condenser GC and 5 grid leak GL so as to cause said triode to operate as a leaky grid detector. This detector is resistance-capacity coupled to a further triode V_5 whose output is resistance-capacity coupled to the aforementioned "common" triode amplifier 10 V_3 . The output from the "common" amplifier is further amplified, if desired, e. g., by valves V_6 , V_7 and applied to a neon lamp NL or equivalent picture building device incorporated in the television picture synthesizing apparatus. The output 15 from the detector V_4 energized from the open aerial system B is also applied to a further amplifier containing any predetermined number of stages, this amplifier being adapted to select and amplify the synchronizing signals for the television transmission and to apply these amplified synchronous signals to control the electric motor or like device, not shown, driving and/or synchronizing the television scanning apparatus. In the figure this further amplifier consists of two valve 20 stages V_8 , V_9 coupled together in cascade. The valve V_8 has in its plate circuit a neon lamp or other glow discharge lamp GL' and the ignition voltage of this lamp is such and the remaining constants of the circuit are such that the said lamp GL "breaks down" only when the synchronizing pulses, which are of an amplitude substantially greater than the peak amplitude of the picture signals, appear in the anode circuit of the valve V_8 . Thus the valve V_9 is energized by 25 synchronizing pulses only and the output from this valve is employed for energizing the synchronizing winding, not shown, of the motor driving the television scanning apparatus, not shown.

It will be seen that with the above described 30 arrangement when the signals from the aerials A and B are equal or nearly equal, the result of their mixture in anti-phase at the grid of the valve V_3 will be such as nearly to eliminate any image, i. e., there will not be a clear picture built up by the lamp NL . When, however, the frame aerial at A is turned in such a direction that the signals picked up thereby approximate to zero, a clear positive picture will be built up by the lamp NL and the existence of this clear positive picture will indicate that the frame aerial has been turned in the direction of the station being received. Of course, the rotatable frame aerial may be replaced by mutually perpendicular fixed frames associated with a radiogoniometer. 35

65 A receiving station in accordance with the present invention may be employed to receive signals from transmitting stations as described in the specification of co-pending application Serial No. 672,552 above referred to; for example, the transmitter may be such that the major intelligence comprising an image of a moving scale station, identification letters, and synchronizing impulses are transmitted by an omni-directional aerial and a minimum indicating signal, such as a 40

70

75

vertical bar appearing across the picture, is transmitted by a revolving frame.

Where a receiver in accordance with the present invention is utilized in conjunction with a transmitter as just described the minimum indicating signal, the vertical bar, will appear clearly only when the receiving frame is correctly oriented towards the transmitting station. 5

Having thus described our invention and the operation thereof, what we claim is:

1. A receiving television station for use for bearing finding and similar purposes comprising, a frame or equivalent directional receiving system, an open aerial or equivalent substantially non-directional receiving system, a television scanning and picture synthesizing system, circuits connecting the receiving systems and the television and synthesizing system, means for building up by means of said scanning and picture synthesizing system a picture derived from signals received upon the substantially non-directional aerial system, and means for superimposing upon said signals, signals of reverse phase derived from the directional aerial system. 10

2. A receiving station as claimed in claim 1 comprising in addition a detector connected with the directional system and a low frequency amplifier following the detector energized from the directional system for producing the phase reversal. 15

3. A receiving station as claimed in claim 1 comprising in addition means for obtaining the required phase reversal comprising different types of detection means for detecting the signals received from the directional system and from the non-directional system respectively. 20

4. A receiving station as claimed in claim 1 comprising in addition means for independently and separately detecting the signals received upon the non-directional aerial system and upon the directional aerial system means for combining the outputs from the two detectors, in antiphase relation, and a common amplifier for amplifying the combined signals for controlling the picture reproducing device of the television receiver. 25

5. A station for receiving wave energy on which synchronized impulses have been impressed in addition to the television signals comprising a directional aerial, a vertical aerial, a television scanning and picture synthesizing system, signal relaying circuits connecting the aerial systems to the television and synthesizing system, driving means for said television scanning and picture synthesizing system, means for building up by means of said scanning and picture synthesizing system a picture derived from the relay connected with the vertical aerial, means for superimposing upon said signals, signals of reverse phase derived from the relay circuit connected with the directional aerial, means connected with the relay connected to the vertical aerial for separating the synchronizing impulses from the signals picked up by the vertical aerial, and means for utilizing said impulses for synchronizing the driving means for the receiving television scanning system. 30

6. The method of receiving the wave energy of a single carrier frequency on which synchronizing impulses and electro-optical representations are impressed by modulation which includes the steps of setting up oscillatory energy characteristic of the electro-optically modulated carrier wave energy and of the direction of propagation of said wave energy, setting up oscillatory energy characteristic of the carrier wave energy modulated by synchronizing impulses and non-characteristic of the direction of propagation of said wave en- 35

ergy, and combining said energies to produce visual representations characteristic of the direction of propagation of said energy, and controlling said combining in accordance with the impulses in said oscillations non-characteristic of the direction of propagation of said wave.

5 7. A receiving television station for use for bearing finding and similar purposes comprising a frame aerial or equivalent directional receiving system, an open aerial or equivalent substan-

tially non-directional receiving system, an electro-optical signal producing means, circuits connecting both of said receiving systems to said electro-optical signal producing means, means for positioning the electro-optical signals in space, and a separate circuit connecting said non-directional receiving system or equivalent structure to said electro-optical signal producing means.
